UNITED STATES PATENT OFFICE.

LEONARD D. POWERS, OF KENESAW, NEBRASKA.

BURIAL-VAULT.

1,106,889.

Specification of Letters Patent.

Patented Aug. 11, 1914.

Application filed May 23, 1913. Serial No. 770,451.

To all whom it may concern:

Be it known that I, LEONARD D. POWERS, a citizen of United States, residing at Kenesaw, in the county of Adams, State of Nebraska, have invented certain new and useful Improvements in Burial-Vaults; and I do hereby declare the following to be a full, clear, and exact description of the invention, such as will enable others skilled in the art to which it appertains to make and use the same.

The present invention is directed to improvements in burial vaults.

The invention has for its object to construct a device of this character from cement so that the same when in use will be waterproof, air tight, and practically burglar proof.

A further object of the invention is to provide a vault of this type which will last indefinitely, and one which may be manufactured at a minimum cost.

A still further object of the invention is to construct a device of this character from sections, which may be easily and quickly connected to form a single casket receiving vault.

A still further object of the invention is to provide the bottom of a vault with rests for receiving the casket after being lowered, said rests being so arranged that the lowering straps may be easily removed after the casket is supported upon the rests.

With these and other objects in view, this invention resides in the novel features of construction, formation, combination and arrangement of parts to be hereinafter more fully described, claimed and illustrated in the accompanying drawing, in which:—

Figure 1 is a side elevation of the vault. Fig. 2 is a longitudinal sectional view. Fig. 3 is a plan view of the bottom sections, the top removed. Fig. 4 is a sectional view on line 4—4 of Fig. 1. Fig. 5 is an end view. Fig. 6 is a sectional view on line 6—6 of Fig. 1. Fig. 7 is a top plan view. Fig. 8 is a sectional view on line 8—8 of Fig. 7.

Referring to the drawing, the numeral 1 designates the bottom of the vault, which is formed from outer sections 2, and an intermediate section 3. The inner edges of the sections 2 are beveled as at 4, which correspond to the beveled outer edges 5 of the intermediate section 3, so that when the sections forming the bottom are abutting there will be a tight fit at these edges. The up-

per surfaces of the outer sections 2 are provided at their inner edges with bevels 6 which form in conjunction with the bevels 7 formed upon the outer ends of the intermediate section 3 channels 7', and in which is poured cement in liquid form so as to form a water-tight joint at these points.

The sides 8 consist of a pair of sections 9, which have their outer ends formed with V-shaped grooves 10, and their inner or meeting ends formed with V-shaped grooves 11 and tongues 12 which interlock. To hold the meeting ends of the sections 9 positively connected plates 13 are provided and are placed upon the inner and outer surfaces of said sections, said plates being engaged by bolts 14 which firmly hold the plates clamped.

The sections 2 and 3 forming the bottom 1 are provided upon their upper surfaces with alined ribs 15, which are triangular in cross section so as to engage the V-shaped grooves 16 formed in the lower edges of the sections 9 of the sides 8. The outer sections 2 are provided upon their upper surfaces with ribs 17, which extending transversely thereof and are triangular in cross section, so as to be engaged by the V-shaped grooves 17' formed in the lower edges of the ends 18. The ends are provided upon their inner faces with ribs 19, which are also triangular in cross section and engage the V-shaped grooves 10 formed in the outer ends of the side sections 9.

The top 20 is formed from outer sections 21, and an intermediate section 22, the meeting edges of said sections being beveled as at 23, so as to insure a tight joint. The meeting edges of the sections 21 and 22 are so formed as to provide a V-shaped groove 24 to receive cement to seal the joint when the vault is set up. The under surfaces of the sections 21 and 22 are provided with alined ribs 25, which are triangular in cross section and engage the V-shaped grooves 26 formed in the upper edges of the sections 9 of the sides 8. Similarly shaped ribs 27 are formed transversely of the section 21, and adajacent their outer edges, and engage the V-shaped grooves 28 formed in the upper edges of the ends 18. Embedded in the sections 21 of the top are reinforcing elements 28', the same being arranged in converging relation and have their outer ends overlapping and provided with registered perforations 29. The intermediate section

22 of the top has embedded therein parallel arranged reinforcing elements 30, which have their ends perforated so as to register with perforations 31 formed in the inner 5 ends of the elements 28'.

Embedded in the outer sections 2 of the bottom 1 are the lower ends of the rods 32, which pass upwardly through the sections 9 of the sides 8, and thence through 10 the sections 21 of the top, thus engaging the perforations of reinforcing elements 30 and 31, after which clamping nuts 33 are applied to their upper projected ends. Similar rods 34 are provided, and have their 15 lower ends secured to the outer ends of the bottom sections 2, said rods passing through the end sections 18 and sections 21 of the top, and are engaged by clamping nuts 35. The upper ends of the rods pass through 20 the perforations 29 of the reinforcing elements.

Formed near the side edges of the bottom sections 1 and 2 are alined ribs 36, the ribs upon the outer sections 2 being connected 25 at their outer ends by transversely arranged ribs 37. The ribs 37 are so arranged as to be spaced a short distance from the inner surfaces of the ends 18, and the ribs 36 are similarly arranged in respect to the inner 30 faces of the side sections 9, so that when the end and side sections are in their set up position cement may be poured in the spaces between said sections and ribs to 35 form a liquid seal to prevent moisture and water from entering the interior of the vault.

Formed transversely of the outer sections 2 of the bottom are rests 38 for supporting the casket when the same is placed in the

vault, thus holding the bottom thereof 40 spaced from the bottom of the vault so that the lowering straps may be easily removed.

Formed integral with the rods 32 are rods 39 which have their outer ends arranged to project through the ends 18, so as to receive 45 clamping bolts, thereby firmly holding the ends in place.

From this construction it will be seen that vault has been provided which is composed 50 of a plurality of sections, which may be easily and quickly set up, and one in which means are provided for permitting the ready removal of the usual casket lowering straps.

What is claimed is:—

A burial vault having a bottom, sides and ends, a top formed from outer sections and an intermediate section, the outer sections having convergingly disposed reinforcing elements embedded therein, parallel arranged reinforcing elements embedded in the intermediate section and having their ends overlapping the inner ends of the converging elements, vertical rods embedded in the sides and having their upper ends engaged with the elements at their overlapping points, horizontal rods embedded in the sides and having their inner ends connected to the vertical rods, and their outer ends extended from said ends, as and for 70 the purpose set forth.

In testimony whereof, I affix my signature, in the presence of two witnesses.

LEONARD D. POWERS.
